UNITED STATES PATENT OFFICE.

WILLIAM C. P. BALDWIN, OF HOLYOKE, MASSACHUSETTS.

WOMAN'S REVERSIBLE AND ADJUSTABLE HOUSE-DRESS.

1,112,248.

Specification of Letters Patent. Patented Sept. 29, 1914.

Application filed February 13, 1913. Serial No. 748,080.

To all whom it may concern:

Be it known that I, WILLIAM C. P. BALDWIN, a citizen of the United States of America, and resident of Holyoke, in the county of Hampden and State of Massachusetts, have invented certain new and useful Improvements in Women's Reversible and Adjustable House-Dresses, of which the following is a full, clear, and exact description.

This invention relates to a woman's house dress which is made as a one-piece garment with waist and skirt forming portions, either end of each of which portions is adapted to lap over the other end thereof and to extend across the front and around to the sides of the garment for reversibility, and so that when one of the front portions shall have become soiled the other one may be brought outermost to present a fresh and clean appearance, such garment having slit openings at the sides of its waist line portion with fastening means comprising a band or the like having connections with the garment front portion and adapted to be passed through the side slit and to have an encircling relation and confinement at the waist line portion.

The objects of the invention are to provide a garment of the above description which shall be of comparatively simple and inexpensive character, susceptible of adjustment whereby it may be made to fit persons having varying waist measurements and also adapted for having the waist line at which the securing band or belt is provided higher or lower as required. The garment also is provided with means for acquiring different effects at the back as may be suited to the taste of the wearer.

The invention is described in conjunction with the accompanying drawings and is set forth in the claims.

In the drawings:—Figure 1 is an elevation showing the one-piece garment as in spread out condition, exposing the inner side thereof. Fig. 2 is a front view of the dress as worn. Figs. 3, 4 and 5 are rear elevations of the dress to show the different effects at the back, which may be imparted thereto. Fig. 6 is a cross sectional view through the belt or waist band taken on line 6—6, Fig. 1. Figs. 7 and 8 are cross sectional views of the garment taken at the waist line and showing the changes in the relations of the parts necessary to procure

the effects represented in Figs. 3, 4 and 5 respectively.

Although the garment is referred to as a one-piece dress, it, of course, may be made of several sections of fabric united by seams 60 as indicated in Fig. 1.

The dress comprises waist and skirt portions *a* which are continuous one with another and either end of each of which is adapted to overlap the other end thereof and to extend 65 across the front and around the sides of the garment,—the back portion *d* being continuous from the neck band to the lower hem of the skirt. The dress has vertical slit openings *f* at its sides adjacent or slightly 70 above its waist line portions, and it has fastening means such as buttons and button-holes *e*, *e*² along different portions of the lengths of said openings for closing such openings as to portions of their lengths. 75 The reversible and overlapping front portions *a* have at their edge portions at the waist line correlated fastenings, such as glove snaps comprising male and female members 10 and 12 whereby the relatively 80 outermost one of such portions *a* may have its edge portion attached to the side of the dress, that is, where each front portion is extended around to about under the arm scye, and is continued by what may be re- 85 garded as the dress back. As shown, the female members 12 are provided externally at the dress sides and the male fastenings or studs 10 internally at the edge portions of the reversible fronts. Opposite each male 90 fastening 10, that is, on the outer side of each front forming portion *a*, is another fastening member 13 to receive detachable connection therewith of one end of a belt forming band *h*. Each such fastening member 95 13 may be a male member of a glove fastening, the coöperative female member 14 of such fastening device being provided at the inner side of the belt *h* near its end. The belt *h* comprises an elastic portion *h*² and a 100 non-elastic portion *h*³, such non-elastic portion being of a length sufficient to entirely encircle the dress at the waist-line. The non-elastic portion *h*³ is tubular for a considerable portion of its length, with the space therein opening to its end at which the elastic portion *h*² is connected, so the one portion may telescope into the other for lengthening and shortening the belt. The 105 elastic portion *h*² has a series of holes 15 110

along its length, and the non-elastic portion h^3 has a button-hole 16 through its outer layer of fabric near its inner end, and also a button-hole 17 at its outer end. A button, 5 stud or other fastening member 18 secured, for example to the inner layer of the fabric of the tubular portion h^3 , serves as a fastening for securing the portions h^2 and h^3 together and such fastening member 18 protruding through the button hole 16 performs the double duty of serving in coöperation with the button hole 17 in the outer 10 end of the belt to confine such belt in its encirclement around the dress. As shown in 15 the cross sectional views in which the portions and relations of the parts are exaggerated and distorted for increased clearness of illustration, the elastic portion h^2 of the belt is supported by the snap catch engagement of the female fastening member 20 14 with the stud 10 which inwardly projects from the edge portion of the innermost front portion a , here shown at the left of the views; the said portion h^2 thence extends 25 through the left hand slit opening f and is continued entirely around the dress at the waist line and slightly overlaps on itself. The button or stud 18 engaging through the button hole 17 confines the outer or free end 30 of the belt and maintains it closely about the person, lending a neat appearance to the outfit. The overlapping and confinement of the said free or outer end of the belt to a portion of itself, conceals the elastic portion 35 h^2 which latter from its nature is of a more unfinished appearance than that of the non-elastic and entirely encircling portion h^3 . Supposing the relatively innermost front portion is wanted outermost to overlap and 40 conceal the already worn or soiled outermost front portion, the desired reversal is most easily and quickly accomplished. The free end of the belt is unfastened and the inner end of its elastic portion is detached 45 from what is shown as the left hand edge portion of the inner dress front and transferred to connection with the inwardly protruding stud 10 of the other dress front, the belt being passed through the right hand 50 slit opening f , carried to encircle the waist, overlapped on itself and secured by the button 18 carried by itself.

Internally of the back portion of the dress at the waist line are a plurality of fastening members 19 such as male members of glove snaps, buttons or studs, here three being shown, one at the middle and the other two spaced laterally therefrom. 55

j represent a plurality of tapes vertically arranged, secured to the dress back at their upper and lower ends and forming stay-loops. 60

m represents an elastic band,—shown displaced in Fig. 1, the same having a plurality of fastening devices for coöperation 65

with the aforementioned fastening members 19, such, for instance, as buttonholes 20 or female members of glove snaps. Such buttonholes or snap members 20 are arranged spaced but closer together than are the fastening members 19. By different dispositions of the fabric comprised at the back of the dress and also of the elastic back strip or band m , different effects as respectively represented in Figs. 3 and 7, 4 and 8, 70 and 5 and 9, may be acquired,—the first mentioned one being that of a broad external plait or panel, the second an internal or partially concealed plait, and the third that of a series of vertical gatherings. In 80 some of the instances the elastic band will have different buttonholes or fastenings thereof engaged with the studs 19 from what will be the case in other of the instances, and in some of the examples the elastic band has only its end portions engaged within and through the tape loop while otherwise it may be throughout its entire length engaged in and through all of such loops, as will be apparent from the 90 cross sectional views in Sheet #2 of the drawings.

The dress is adjustable as to girth or dimension of its waist line by reason of the last described provisions and the encircling 95 belt h is also adjustable by reason of the elastic portion being telescopic in the encircling portion and susceptible of being fastened by means of its buttonhole engagement with the button or stud 18, whereby 100 the belt as a whole is distended or contracted.

Although the reversible front portions a have been referred to as continuous and inclusive of the waist-front and skirt-front forming portions and are to all intents and purposes so continuous while the garment is being worn, I have shown in Fig. 1 that at the waist line such dress fronts are severed by horizontal slashes extending from their edges to points at the garment sides about under the arm scyes. The portions indicated by o and t , and separable as mentioned on substantial horizontal lines, are of such vertical dimensions that the lower extremities of the waist portions are overlapped by the upper extremities of the skirt portions; and means are provided for securing these parts together while having any degree of overlapping adjustment, such means in the present instance consisting of a button 22 at the lower outer corner of the waist section and a series of vertically arranged button holes 23 at the upper outer corner of the skirt-front forming button. By having each portion 22 engaged through either of the several buttonholes 23, the skirt may be raised or lowered for a modification of the waist-line of the garment and in conjunction with such adjustment, the slit openings 110 115 120 125 130

it may have relatively opened and closed portions higher or lower as the case may require.

It being entirely a matter of preference as to what particular form of fastenings may be employed at the various points or places in the garment forming the subject matter of this invention, it is to be understood to be immaterial whether I employ glove snap fastenings, buttons and buttonholes, button holes and studs, or in some cases hooks and eyes, as any one of these species of fastenings is the equivalent of another; and I may, moreover, employ one of the mentioned kinds of fastenings in some places and other of the kinds of fastenings in other places in the garment.

I claim—

1. A dress comprising continuous waist and skirt portions and formed at its waist line with slits, either end of each of which portions is adapted to be lapped over the other end thereof and to extend across the front and around the adjacent side of the wearer for reversibility; in combination with correlated duplicated means located adjacent the waist line for fastening the relatively outermost of such portions in overlapped position; a belt comprising telescoped elastic and inelastic portions adapted to be detachably secured at one end to the edge of the relatively innermost portion, inserted through the adjacent slit and passed entirely around the dress at the waist line, the other end of said belt being adapted to be overlapped and secured upon itself; and means for retaining the said belt portions in adjusted position relatively to each other.

2. A garment of the character specified having reversibly overlapping front portions and a belt adapted to be detachably connected at one end to one of such portions and to be passed completely around the waist line of the garment and overlapped and secured upon itself at its other end, said belt comprising telescopically arranged elastic and inelastic portions having correlated means for retention thereof in adjusted position relatively to each other.

3. A garment of the character specified having over-lapping front portions and a belt adapted to be detachably connected at

one end to one of such portions and to be passed completely around the waist line of the garment and over-lapped and secured upon itself at its other end, said belt comprising an elastic portion and a tubular inelastic portion adapted to receive said elastic portion and of sufficient length to completely encircle the garment at the waist line, said belt portions being provided with correlated means for retaining them in adjusted position relatively to each other.

4. A dress comprising waist and skirt front portions adapted either to adjustably overlap the other and to extend across the front and around the sides of the dress, said overlapping front portions being separated at the waist line and of such vertical dimensions that the lower extremities of the waist portions may be lapped across the upper extremities of the skirt portions, and means for securing said portions in such adjusted overlapping position.

5. A woman's dress having reversible fronts and means for confining them in either of their overlapping relations, and said garment having at its back portion at the waist line a detachable elastic strip or band, and means for securing such strip at different portions of its length in either its normal or in its stretched condition.

6. A garment of the character described having within its back portion at the waist line a plurality of fastening members, an elastic band having a plurality of fastening members, one of the sets of fastening members having spacings different from those of the other set.

7. A garment of the character described having within its back portion at the waist line a plurality of fastening members, an elastic band having a plurality of fastening members, one of the sets of fastening members having spacings different from those of the other set, and a plurality of vertical loop-forming tapes secured at their upper and lower ends to and at the inner side of the back portion of the garment.

Signed by me at Springfield, Mass., in presence of two subscribing witnesses.
